(57) **CLAIM**

The ornamental design for a desk, as shown and described.

DESCRIPTION

FIG. 1 is a perspective view of a desk, showing a first embodiment of the new design;

FIG. 2 is a left side view thereof, the right side being an identical image thereof;

FIG. 3 is a front view thereof, the rear view being an identical image thereof;

FIG. 4 is a top view thereof;

FIG. 5 is a bottom view thereof;

FIG. 6 is a perspective view of a desk, showing a second embodiment of the new design;

FIG. 7 is a left side view thereof, the right side being an identical image thereof;

FIG. 8 is a front view thereof, the rear view being an identical image thereof;

FIG. 9 is a top view thereof; and

FIG. 10 is a bottom view thereof;

FIG. 11 is a perspective view of a desk, showing a third embodiment of the new design;

FIG. 12 is a left side view thereof, the right side being an identical image thereof;

FIG. 13 is a front view thereof, the rear view being an identical image thereof;

FIG. 14 is a top view thereof;

FIG. 15 is a bottom view thereof;

FIG. 16 is a perspective view of a desk, showing a fourth embodiment of the new design;

FIG. 17 is a left side view thereof, the right side being an identical image thereof;

FIG. 18 is a front view thereof, the rear view being an identical image thereof;

FIG. 19 is a top view thereof; and,

FIG. 20 is a bottom view thereof.

A right-side view and a rear view of the desk are omitted since the right-side view and the rear view are respectively identical to the left-side view and the front view.
